SHIPPING BLOCK

Trafton D. Smith, Pontiac, Mich.

Application October 24, 1940, Serial No. 362,503

3 Claims. (Cl. 105—367)

This invention relates to shipping blocks for use in connection with railroad cars or vehicles for shipping stacks, bundles, or coils of metal from one destination to another, and more particularly to a shipping block or blocks on which the bundles can be firmly secured, thus preventing displacement of the pieces making up the bundles, and eliminating bending, jamming, or otherwise damaging of the ends and edges of the material.

One of the prime objects is to design a shipping block for spacing the bundles from the floor of the carrying vehicle, and to facilitate the fastening or wrapping of cables, chains, or other means around each bundle so that it may be handled by suitable hoisting mechanism such as a crane or the like.

Another object is to design a shipping block of rigid, substantial construction provided with upturned ends so that there will be no gouging of the floor or support when the bundles shift on the floor, due to sudden stops or other rough handling of the railroad car.

A further object is to provide a shipping block provided with slots and openings to facilitate the anchoring of wire, straps, or other flexible tying means thereto, so that the individual pieces or members can be readily strapped or tied in bales or bundles etc.

A further object still is to design a shipping block of substantial construction which can be quickly and easily handled by a workman; which readily fits in a suitable pocket in the car; and which is adaptable for use over and over again as occasion demands.

With the above and other objects in view, the present invention consists in the combination and arrangement of parts, hereinafter more fully described, illustrated in the accompanying drawings, and more particularly pointed out in the appended claims, it being understood that changes may be made in the form, size, proportions, and minor details of construction, without departing from the spirit, or sacrificing any of the advantages of the invention.

In the drawings:

Fig. 1 is a part sectional, side elevational view of a railroad car showing bundles of sheet steel plates mounted on my shipping blocks, each bundle being separately strapped or tied;

Fig. 2 is a transverse sectional view thereof;

Fig. 3 is an enlarged detail, side elevational view of the shipping block;

Fig. 4 is a top plan view thereof;

Fig. 5 is an end elevational view;

Fig. 6 is a transverse sectional view taken on the line 6—6 of Fig. 3; and,

Fig. 7 is an enlarged fragmentary, side elevational view showing a shipping block with plates mounted thereon.

In shipping bundles of steel plates, coils, etc., from one location to another, it is at present general practice to utilize lumber for skids and bracing in the cars. This requires timbers or pieces 10 of sufficient size and strength to support the bundles which are of considerable weight; in fact, so heavy that a crane or other power lifting device is required for the loading and/or unloading operation. When the bundles are unloaded etc., 15 these timbers are discarded and become waste lumber which is not again utilized for the same purpose, as it is usually split, gouged, and otherwise damaged. This is quite expensive and not always conducive to neat, tight bundling; and I have therefore designed a shipping block which 20 serves to space the material from the floor of the car so that cables or chains used for hoisting, when loading or unloading, can be readily passed around it, which also serves as a skid, to eliminate gouging of the floor of the car should the 25 bundles shift when enroute to its destination, and which is also provided with spaced slots of a size to accommodate the tying wire or straps so that the blocks are readily adapted to any size or 30 shape bundle, these blocks being of a size so that they can be readily placed in a suitable pocket in the bottom of the car and used over and over again as required.

Referring now more specifically to the drawings in which I have shown the preferred embodiment of my invention, the numeral 7 indicates the body of a conventional railroad car mounted on wheels 8 which engage tracks 9 as usual.

40 The shipping blocks 10 are preferably H-beam shape in cross section, and are relatively light in weight so that they can be readily handled by a workman. Spaced apart openings 11 are provided in the web 12, and sections 13 are punched 45 from the ends of each block, at a point directly adjacent the bottom flange 14, to permit the end section 15 of the flange to be bent upwardly and form a skid to permit the blocks to move or shift without gouging the floor or surface on which 50 they rest.

Slots 17 are provided in the upper flange 16 of each block in spaced apart relation, and are adapted to accommodate steel straps or wires 18 used for tying and securing the bundles S on 55 the shipping blocks, the upper outer flange be-

ing turned as at 19 to eliminate sharp edges which might otherwise cut or weaken the tying members.

These blocks can be of any desired length, but I find it advantageous to make them comparatively short, and place two or more in end to end abutting relation to form a sectional skid to suit the length of the material to be bundled.

The edges of the material can be further protected by placing a heavy sheet of cardboard or similar material C on the top and bottom of the pile.

After the material has been placed in a bundle on the shipping blocks, the steel strap or wire 18 is inserted in the exposed slot which is closest to the end of the bundle, this strap thence leading up and over the bundle and thence down and through the nearest exposed slot on the opposite end of said bundle, where it is pulled tight and firmly secured in any desired manner. The opposite end of the bundle is tied in a similar manner, after which the bundle is tied in the opposite direction by leading similar straps or wires 20 through the openings 11, thence up and over the bundle, the ends being tied in the usual manner to form a tightly bound, compact bundle which prevents the pieces forming said bundle from shifting with relation to each other, eliminating bending or otherwise damaging the edges of the sheets or members.

The bundles are of course of considerable weight and are usually handled by a hoisting crane or the like (not shown) for transfer from a loading dock to the car, or from the car to a warehouse or platform, and a cable or chain sling (not shown) is used for this purpose.

Upon arrival at destination, the wire straps 18 and 20 are severed and the material placed in the warehouse or stock-room or routed as desired, the shipping blocks being then placed in a suitable compartment or pocket (not shown) in the car, for use over again when required, these compartments being locked with the usual railroad car seal in the conventional manner.

From the foregoing description, it will be clearly obvious that I have perfected a very simple, practical, and inexpensive shipping block which is usable over and over again.

What I claim is:

1. A metallic shipping block, H-beam shape in cross section with one edge of the upper flange turned downwardly, sections cut from the web of said block at the ends and adjacent the lower flange to permit the ends of the lower flange to be upturned to form a skid, spaced apart transversely disposed slits in the one edge of the upper flange, and spaced apart openings in the web of said block.

2. A shipping package comprising spaced apart metallic members, H-beam shape in cross section, each member having one edge of its upper flange turned downwardly with the ends of the lower flange turned upwardly to form skids, a stack of metal sheets positioned on said metallic members, a plurality of spaced apart transversely disposed slits provided in the turned upper flange, straps extending beneath the lower face of the slit flange of the metallic member and leading upwardly through certain slits directly adjacent the front and rear edge of the sheets and encircling the stack, and spaced apart openings formed in the web of said metallic members for accommodating straps extending through said openings and encircling said stack in the opposite direction.

3. A shipping package comprising a plurality of spaced apart metallic members, H-beam shape in cross section, the ends being shaped to permit the end portions of the lower flanges to be bent upwardly to form skids, a stack of metal sheets positioned on said metallic members, each member having one upper flange edge turned downwardly and having a plurality of spaced apart transversely disposed slits provided therein, straps disposed beneath the turned upper flange of the metallic member with the ends leading upwardly through slits directly adjacent the edges of the stack and encircling said stack, spaced apart openings in the vertical web of the metallic members, and straps extending through said openings and encircling said stack in the opposite direction.
